UNITED STATES PATENT OFFICE.

ORVILLE R. OSMUN, OF COVINGTON, KENTUCKY.

LIFTING-JACK.

1,312,568.

Specification of Letters Patent.

Patented Aug. 12, 1919.

Application filed April 10, 1919. Serial No. 289,046.

To all whom it may concern:

Be it known that I, ORVILLE R. OSMUN, a citizen of the United States, and residing at Covington, in the county of Kenton and 5 State of Kentucky, have invented a new and useful Improvement in Lifting-Jacks, of which the following specification is a full disclosure.

My invention relates to lifting-jacks of 10 the ratchet pawl type operated by a rocking lever and contemplates a jack of this character which is raised or lowered in stepped movements by coöperating pawls and toothed standard or raised or lowered 15 in a single movement as when adjusting the jack to or from the load to be lifted.

An object of the invention is to provide 20 a jack of this type in which the pawl movements are controlled to determine the direction of jack movement and in which said control is accomplished by a lateral translation of the operating handle.

A further object is to provide for a quick 25 and convenient removal of the handle from the jack.

The features of the invention will be more fully set forth in the description of the drawings, forming a part of this specification, in which:

30 Figure 1 is a side elevation of the jack as adjusted for raising a load.

Fig. 2 is a similar view, partly in section, showing the adjustment for lowering a load.

Fig. 3 is a plan section on line 3, 3, Fig. 1.

35 Fig. 4 is a vertical section on line 4, 4, Fig. 2.

Fig. 5 is a detail elevation of the inner end of the operating handle.

Referring more particularly to Figs. 1 and 40 2, a base 1 supports a toothed standard 3, having opposing series of ratchet teeth 4, 5.

A hollow lifting head 6 telescopically engages over the standard 3 and is provided with a cap or head 7 suitably formed for engaging 45 the object to be lifted and with a side ledge or step 8 for engaging objects at low elevation. The head 6 is retained in engagement with the standard 3 by a pin 9 projecting into an elongated slot 10 in said head and limiting the movement thereof.

50 11, 12, represent ears depending from the head 6 on either side of the standard 3. 13 represents an operating rock lever having a rectangular hollow frame portion 14, pivoted at 15, 15, on the ears 11, 12, of the 55 head 6, and a handle receiving portion 16,

which is slotted to receive the removable handle 17. Gravity ratchet pawls 18, 19, are positioned within the frame portion 14 of the rock lever 13 and are pivoted respectively on pivot studs 20, 21, at opposite sides of the toothed standard 3.

From the above it will be evident that a rocking movement of the lever 13 will cause the pawls to alternately engage the 65 teeth of the standard to raise the jack-head 6, and also to bring the head quickly into engagement with the object to be raised. The lever 13 and head 6 may be bodily lifted by the handle 17, the pawls in this instance 70 idly ratcheting over the standard teeth. After the head 6 is free of the load it may be quickly lowered by grasping the upper ends of the pawls and pinching them together to disengage their lower ends from 75 engagement with the teeth of the standard 3.

To provide for a step by step lowering operation, the following mechanism is employed:

80 Each of the pawls 18, 19, have trip fingers 25 projecting inwardly upon one side of the standard 3. A square shanked plunger 26 slides within a square cored recess in the head 6 and is urged downwardly by a spring 85 27. The lower end of the plunger is of stepped form providing a pawl engaging shoe portion 28 and a limb 29 alined with and adapted, when the plunger is released, to engage the lever 13, thereby limiting the 90 downward movement of said plunger. A control slide 30 has a beveled wedge nose 31 and a downwardly extending guide limb 32 slidable within a slot 33 in the lever 13. A square stud 34 projects laterally from 95 said slide and engages into one of a pair of notches 36 formed in the opposite edges of the operating handle 17. This provides a unitary movement of the handle and slide.

In Fig. 1 the handle 17 is shown pushed 100 inwardly, the wedge nose 31 of the slide having engaged under and elevated the plunger 26 to raise its pawl engaging shoe portion 28 out of a pawl engaging position. When the handle 17 is withdrawn, as shown 105 in Fig. 2 the slide 30 is removed from beneath the plunger and allows it to be forced downwardly by its spring. In this position the shoe portion 28 will alternately engage the pawl finger 25. As shown, the pawl 19 110 had been tripped during the upward movement of the operating lever. Upon lowering

said lever the pawl 19 will engage the next lower tooth 5 of the standard and after said pawl has come to rest the handle 17 is given a slight additional downward movement to 5 elevate the pawl 18 causing its finger 25 to engage the plunger shoe 28 and trip said pawl for a subsequent lowering step movement of the head. The handle 17 can be quickly and conveniently removed by manually raising the slide 30 to disengage the square stud 34 from the handle notch 36. A pin 38 prevents the slide 30 from being removed from the lever 13.

Having described my invention, I claim:

15 1. A lifting-jack comprising a standard, having opposed series of ratchet teeth, a lifting head slidably mounted on the standard, an operating member pivotally connected to and movable with said lifting head, opposed ratchet pawls pivoted on the operating member at opposite sides of the standard, means controlling the operations of the pawls, a second means operable to disable said first means, and a handle capable of longitudinal movement to operate said second means.

2. A lifting-jack comprising a standard, having opposed series of ratchet teeth, a lifting head slidably mounted on the standard, 30 operating mechanism for raising or lowering said head in stepped movements, means controlling said mechanism, an operating handle and a device operated by a longitudinal translation of the handle for rendering said control mechanism ineffective.

3. A lifting-jack comprising a standard having opposed series of ratchet teeth, a lifting head telescopically slidable on said standard, operating mechanism carried by 40 said head and coöperating with the standard for raising or lowering the lifting head, an abutment member movable to engage and control said operating mechanism, an operating handle and a device operated by said handle for engaging the abutment member to render it ineffective.

4. A lifting-jack comprising a standard having opposed series of ratchet teeth, a lifting head telescopically slidable on said standard, an operating lever pivoted on the lifting head intermediate of the opposed series of ratchet teeth of the standard, a pair 50 of ratchet pawls respectively pivoted on the operating lever on opposed sides of the lever pivot and each coöperating with an adjacent series of ratchet teeth, a spring plunger providing an abutment coöperating with and controlling the pawls, an operating handle slidably mounted upon the operating lever, and a device removably connected to 60 and movable with the handle, adapted to engage and withdraw said abutment plunger from coöperative relation with the ratchet pawls.

5. A lifting-jack comprising a toothed 65 standard, a lifting head telescopically slideable thereon, an operating mechanism carried by said lifting head, an operating handle, and means operated by a longitudinal movement of the handle for controlling the 70 operating mechanism.

6. A lifting-jack comprising a toothed standard, a lifting head slideable thereon, a 75 rocking operating mechanism for raising or lowering the lifting head by a step by step movement during each rocking movement of said mechanism, and a handle for rocking said operating mechanism, said handle being connected to have a relative independent movement, and means controlled by said 80 independent handle movement for determining whether said operating mechanism shall raise or lower the lifting head.

7. A lifting-jack comprising a standard 85 having opposed series of ratchet teeth, a lifting head telescopically slideable on said standard, an operating member pivotally connected to and movable with said lifting head, opposed ratchet pawls pivoted on the operating member at opposite sides of the 90 standard, a spring member adapted to engage the pawls, a removable handle slideable relative to the operating member and a cam slide actuated by the handle to control the spring member.

8. A lifting-jack comprising a standard 95 having opposed series of ratchet teeth, a lifting head telescopically slideable on said standard, an operating member pivotally connected to and removable with said lifting head, opposed ratchet pawls pivoted on the operating member at opposite sides of the standard, means adapted to engage and control said pawls, a removable handle slideable on the operating member and having a notch and a cam slide engaging into said handle notch and adapted to control said means.

9. A lifting-jack comprising a standard 100 having opposed series of ratchet teeth, a lifting head telescopically slideable on said standard, an operating member pivotally connected to and movable with said lifting head, opposed gravity ratchet pawls pivoted on the operating member at opposite sides 115 of the standard, each having inwardly extending fingers, a spring pressed plunger carried by the lifting head adapted to be positioned to engage said pawl fingers, a handle slideable on the operating member 120 and a cam slide slideable with said handle to control the spring plunger.

10. A lifting-jack comprising a standard 125 having opposed series of ratchet teeth, a lifting head telescopically slideable on the standard, an operating member pivotally connected to and movable with said lifting head, opposed ratchet pawls pivoted on the

operating member at opposite sides of the standard, each having inwardly extending fingers, control means adapted to engage said fingers, a removable handle for rocking the operating member and a device detachably connected to the handle for operating the control means.

In witness whereof, I hereunto subscribe my name, as attested by the two subscribing witnesses.

ORVILLE R. OSMUN.
